UNITED STATES PATENT OFFICE.

PETER A. BROUILLETTE AND ARTHUR R. BECK, OF SIOUX CITY, IOWA, ASSIGNEES OF
ONE-THIRD TO RILEY J. BECK, OF SIOUX CITY, IOWA.

COMBINED PAPER AND PENCIL HOLDER.

Application filed August 30, 1922. Serial No. 585,143.

To all whom it may concern:

Be it known that we, PETER A. BROUILLETTE and ARTHUR R. BECK, citizens of the United States, and residents of Sioux City, in the county of Woodbury, State of Iowa, have invented a certain new and useful Combined Paper and Pencil Holder, of which the following is a specification.

The object of our invention is to provide a combined paper and pencil holder of simple, durable and inexpensive construction, so arranged that it may be easily and quickly applied to the upper edge of the wearer's coat pocket, and when applied it will positively hold a paper document or pencil in such a manner that either the paper document or pencil may be easily removed at the will of the user, and which will positively hold either the pencil or the document against accidental loss.

A further object is to provide a combined paper and pencil holder which may be formed of a single piece of metal and which is provided with folded portions in such a manner that one of the portions may be mounted on the inner side of the pocket, and said inner portion being designed to clamp the pencil and document while the other portion is mounted on the outside of the pocket, and provided with a blank space in which an advertisement may be placed.

A further object is to provide in a combined pencil and paper holder, improved means for retaining the said holder in position.

These and other objects will be apparent to those skilled in the art.

Our invention consists in the construction, arrangement and combination of the various parts of the device, whereby the objects contemplated are attained, as herein-after more fully set forth, pointed out in our claim, and illustrated in the accompanying drawings, in which:

Figure 1 is a perspective view of our improved pencil holder.

Figure 2 is a detail view showing a segmental portion of a coat, and also a portion of a pocket, and the manner in which our improved holder is applied thereto.

Figure 3 is a detail sectional view taken on the line 3-3 of Figure 2, the pocket being shown in dotted lines.

Figure 4 is a detail view showing the holder in blank form as cut out by dies

before the retaining members have been folded.

The numeral 10 indicates a segmental portion of a garment and 11 the upper portion of a pocket for the purpose of illustrating the manner in which our device is applied.

Our improved device is formed with a single piece of metal and blanked in the shape as illustrated in Figure 4, and provided with a rectangular portion 13 and a portion 14 having one edge curved, the said curved edge being provided with an elliptically shaped member 15.

The portions 13 and 14 have their adjacent edges separated by means of a slot 16, the inner end of which is formed with an opening 17. An outwardly extending bead 18 is then formed along the adjoining edges of the members 13 and 14. An outwardly extending bead 19 is also extended transversely through the central portion of the member 14 having one end adjacent to the opening 17 and the other end near one edge of the neck portion between the members 14 and 15. The bead 19 is formed considerably shorter than the bead 18 so that the bead 19 will be more flexible than the bead 18. This bead 19 may be made more flexible by pinching or squeezing the metal thinner as the bead is formed, or it may be produced by forming a notch 20 so that the bead 19 is shorter than the bead 18. The purpose of this will hereinafter be made clear.

The member is then formed by simply folding the member 14 adjacent to the member 13, as clearly shown in Figure 1, with a slight space between them.

The elliptical member 15 has its two pointed ends 21 pulled outwardly toward each other to make the pencil retainer, these ends being so folded that the opening formed thereby will be slightly smaller than the regular size pencil so that when the pencil is in position, the members 21 will be slightly sprung apart. The bead 18 forms a sort of rolled upper edge against which the pencil is supported, as illustrated in Figure 3, thus providing a double means for yieldingly holding the pencil in position.

The upper edge of the member 13 is provided with two inwardly extending retaining members 22 which are formed by punching a portion of the metal 13 inwardly, as clearly shown in Figure 3. These serve

105

110

to form hooks or catches for the purpose of preventing the holder from accidentally coming loose from the pocket. The holder is simply placed over the upper edge of the pocket, as shown in Figure 3, with the members 14 and 15 on the inside of the pocket and with the member 13 on the outside of the pocket. The said members are shoved downwardly until the upper edge of the pocket engages the under surface of the bead 18. A pencil may then be applied in the usual manner, while a paper document indicated by the numeral 23 may be placed between the pointed end of the member 14 and the inside of the pocket. The pointed end of the member 14 is yieldable relative to the fixed portion of the member 14 so that the document will always be yieldingly held in position. By making the bead 19 thus yieldable with the bead 18, it will be seen that the space between the flexible end of the member 14 and the member 13 may be varied without varying the space between the fixed portion of the member 14 and the said member 13, thereby providing means whereby documents of considerable thickness may be clamped in between the pocket and the said flexible member without causing the fixed portion of the member 14 to be separated from the inner face of the pocket to such an extent that the said holder is likely to become loose, as would be the case if the bead 19 was stiffened so that both ends of the member 14 would be spread when the document is inserted.

It will be seen that on account of the stiffness of the member 18, the member 14 will be quite rigidly supported relative to the member 13, and the pocket firmly held against that member 22 which is opposite the fixed portion of the member 14.

The outer face of the member 13 may have any suitable advertisement placed on it, as it is simply a plate with a plain surface. The said member 13 may be made of any convenient size.

Thus it will be seen that we have provided a combined paper and pencil holder of simple, durable and inexpensive construction which may be made of a single piece of material, and which is easily folded into shape, and which may be positively secured to the user's inside coat pocket, and in which either a paper document or pencil may be securely held.

We claim as our invention:

A combined paper and pencil holder formed from a single piece of material having overlapping members parallel and yieldably mounted relative to each other, one of said members being designed to engage one side of a user's pocket and the other member yieldably supported and parallel with the first said member and designed to engage the inner face of the pocket, said second member having yieldably curved pencil supporting portions, the adjacent edges of the first and second members being formed in a cylindrical rib designed to rest on the top edge of the pocket member, the pencil retaining members being so arranged that a pencil when inserted therein will engage said cylindrical rib, said second member being provided with a paper retaining member yieldably mounted relative thereto and to said first member, the adjoining edges of said second member and said yieldable member being provided with a yieldable rib of a greater resiliency than the first said cylindrical rib.

Des Moines, Iowa, August 5, 1922.

PETER A. BROUILLETTE.

ARTHUR R. BECK.
